(57) **CLAIM**

The ornamental design for a television, as shown and described.

DESCRIPTION

FIG. 1 is a front elevational view of a first embodiment of a television showing our new design, wherein the television comprises a translucent face with a light strip behind it; FIG. 2 is a front elevational view of a second embodiment of a television showing our new design, wherein the television comprises a translucent face with a light strip behind it; FIG. 3 is a front elevational view of a third embodiment of a television showing our new design, wherein the television comprises a translucent face with a light strip behind it; FIG. 4 is a front elevational view of a fourth embodiment of a television showing our new design, wherein the television comprises a translucent face with a light strip behind it; FIG. 5 is a front elevational view of a fifth embodiment of a television showing our new design, wherein the television comprises a translucent face with a light strip behind it; FIG. 6 is a partially enlarged front elevational view of the embodiment of FIG. 1 along the lines 6-6 of FIG. 1 showing the translucent face with the light strip behind it;

FIG. 7 is a partially enlarged front elevational view of the embodiment of FIG. 2 along the lines 7-7 of FIG. 2 showing the translucent face with the light strip behind it; FIG. 8 is a partially enlarged front elevational view of the embodiment of FIG. 3 along the lines 8-8 of FIG. 3 showing the translucent face with the light strip behind it; FIG. 9 is a partially enlarged front elevational view of the embodiment of FIG. 4 along the lines 9-9 of FIG. 4 showing the translucent face with the light strip behind it; and, FIG. 10 is a partially enlarged front elevational view of the embodiment of FIG. 5 along the lines 10-10 of FIG. 5 showing the translucent face with the light strip behind it. The broken lines showing the unclaimed portions of the television receiver form no part of the claimed design.

(Continued)

Dot-dash broken lines define the boundaries of, but not included in, the claimed design.

1 Claim, 10 Drawing Sheets
